Primary Examiner — Eliza Z Bennett-Hattan(74) *Attorney, Agent, or Firm* — Baker Botts L.P.(57) **CLAIM**

The ornamental design for a handle for a medical device, as shown and described.

DESCRIPTION

FIG. 1 is a perspective view of a handle for a medical device, showing the new design.

FIG. 2 is a bottom perspective view thereof;

FIG. 3 is a top plan view thereof;

FIG. 4 is a bottom plan view thereof;

FIG. 5 is a left side elevation thereof;

FIG. 6 is a right side elevation thereof;

FIG. 7 is a front elevational view thereof; and,

FIG. 8 is a rear elevational view thereof.

The broken lines in the drawings depict environmental subject matter only and form no part of the claimed design.

1 Claim, 6 Drawing Sheets(56)
